CLAIM

I claim the ornamental design for a rack for suspension of periodicals and other items.

DESCRIPTION

FIG. 1 is a perspective view of the invention; FIG. 2 is a right side view of the invention, the left side view being a mirror image;

FIG. 3 is a top plan view of the invention;

FIG. 4 is a front elevation view of the invention;

FIG. 5 is a bottom plan view of the invention;

FIG. 6 is a rear elevation view of the invention; and,

FIG. 7 is a perspective view of the invention in use mounted to a wall and with periodicals suspended therefrom. The broken lines in FIG. 7 are for purposes of illustration only and form no part of the claimed design.
